U.S. Cl. D95—3

FIG. 1

FIG. 2

FIG. 4

FIG. 5

FIG. 1 is a perspective view of a disposable razor showing my new design; the undisclosed bottom and rear sides are substantially the same as the top and front, respectively;

FIG. 2 is a front elevational view thereof;

FIG. 3 is a top view thereof;

FIG. 4 is an end view on an enlarged scale taken from the left of FIG. 2; and

FIG. 5 is an end view on an enlarged scale taken from the right of FIG. 2.

The dominant features of the design reside in the full line portions of the drawing.

I claim:

The ornamental design for a disposable razor, substantially as shown and described.
